UNITED STATES PATENT OFFICE

JOHN W. COSGROVE, DECEASED, LATE OF MEDFORD, MASSACHUSETTS, BY CAROLINE E. COSGROVE, ADMINISTRATRIX, OF MEDFORD, MASSACHUSETTS, ASSIGNOR TO UNITED SHOE MACHINERY CORPORATION, OF PATERSON, NEW JERSEY, A CORPORATION OF NEW JERSEY

ABRADING MACHINE

Application filed March 6, 1928. Serial No. 259,538.

This invention relates to abrading machines and is herein illustrated as embodied in a machine for buffing or scouring boot and shoe parts.

5 In scouring the breasts of certain types of Louis heels great difficulty has been experienced because of the sharp curvature of the breasts of the heels and the danger that the tool will contact with other parts of the heels or of the shoes which must not be scoured. This work is preferably done upon machines utilizing inflated tools because of the softness of the "touch" of a tool in which the abrasive cover is supported upon a cushion of air, but 10 the dimensions of the available inflated tools have been such that the breasts of certain heels could not be treated.

Accordingly, an object of the invention is to provide an elongated, rotatable, abrading tool of the inflated type having a greatly reduced cross-section. More particularly the invention aims to provide a rotatable, resilient, abrasive tool of simple construction adapted to be mounted upon a supporting 25 spindle and having its component parts so arranged that the requisite mechanical strength is provided for all of these parts and the cross-sectional size of the tool is kept at a minimum.

30 The resilient casing of the illustrated tool is provided at one end with an enlarged portion or flange for cooperation with a shouldered supporting spindle and, in accordance with a feature of the invention, means are provided for clamping this enlarged portion against a shoulder upon the spindle and for positively preventing twisting or rotational movement of the enlarged portion with respect to the spindle.

40 Another feature of the invention consists in providing improved means for holding an abrasive cover, such as a sleeve of emery cloth upon the tool. In the illustrated construction a resilient casing is first mounted upon the spindle to support the abrasive cover and this casing, as well as the cover itself, is secured to the spindle by means constructed and arranged to make an air-tight joint between the resilient casing and the spindle so 45 that the former may be inflated.

Another feature of the invention resides in means for holding the free or outer end of a resilient casing against twisting movement with respect to the spindle on which it is mounted. Since the cross-sectional dimensions of the outer end of the casing which it is desired to hold against twisting movement are relatively small, this anti-twisting means, in the illustrated construction, takes the form of a rigid member of non-circular cross-section, such as a piece of square tubing which is secured to the resilient casing and is arranged to fit a non-circular portion of the spindle.

55 To adapt the tool for inflation, the resilient casing has a closed outer end. As a result, the air pressure inside the tool pushes against this end and tends to stretch the resilient casing axially of the spindle. In order to resist this tendency, anti-stretching means is provided for preventing longitudinal movement with respect to the spindle of the rigid non-circular member which is secured to the outer end of the casing, said means extending to the clamped end of the casing and arranged to be secured by the same clamping device which holds the casing and the abrasive sleeve.

60 These and other features of the invention will now be set forth in detail with reference to the accompanying drawing, in which

65 Fig. 1 is a perspective view of the head of the machine having a tool of improved form mounted upon a horizontally arranged spindle and disposed adjacent to a suction opening of the machine;

70 Fig. 2 is a side elevation of the abrading tool with parts broken away and in section; and

75 Fig. 3 is an exploded view showing a portion of the end of the spindle, the resilient casing with its anti-twisting and its anti-stretching means, and the flanged abrasive cover adapted to be clamped in position thereupon.

80 The illustrated machine, which is of the well-known Naumkeag type, is provided with a suction opening 10, an air pressure chamber 12, a driving belt 14, and a rotatable tool-carrying spindle 16, the spindle 16

being driven through the belt 14 and being adapted to carry an inflatable buffing or scouring tool 18 designed for scouring the breasts of Louis heels. In order to facilitate such scouring operations, the tool-carrying spindle 16 is mounted for rotation about a horizontal axis, directly in front of the suction opening 10, in an auxiliary frame 20 supported by a fixed bracket 22 comprising a series of pipes 24 and elbows 26. One portion of the bracket comprises an elbow T 28 by means of which there is supported a stub shaft 30 carrying idler pulleys 32. Other idler pulleys 34 are mounted upon an adjustable arm 36 to carry a belt 38 to pulleys 40 upon the tool spindle 16. By mounting the tool 18 for rotation about a horizontal axis, the operator is able to present the breast of the heel with the shoe held in such a position that the tread face of the sole is uppermost and the breast of the heel facing the operator. This makes it easy for the operator to inspect the portion of the shoe being treated.

The spindle 16 of the machine is enlarged at 42 to form a shoulder 44 for cooperation with a resilient casing or pad 46. This casing, which is closed at its outer end and is preferably made of molded rubber, is provided with an enlargement or flange 48. An air-tight joint is effected between the spindle and the inner end of the casing by a collar 50. The collar 50, which bears against an anti-friction washer 52 and is internally threaded to engage a threaded portion 54 upon the spindle, clamps the flange 48 of the casing against the shoulder 44 of the spindle. It will be understood that the spindle 16 is provided with an internal air passage 56 terminating in an air-outlet opening 58 provided inside the resilient casing 46 to allow the inflation of this casing. This passage communicates with the pressure chamber 12 through the pipes 24 and a hollow bearing in the auxiliary frame 20. The outer or left end of the spindle 16, as viewed in Fig. 1, upon which the tool is supported, is tapered or conical, as shown at 60, and receives the tubular casing or pad 46 tapered internally and externally in the same direction as the spindle, which is about one-half inch in diameter at its larger end and is reduced to as little as one-quarter inch in diameter at its smaller end thereby to provide a tool the dimensions of which shall render it capable of use with all types of heels and especially adapt it for scouring the breasts of some types of Louis heels.

Because of the very considerable torsional strains upon the casing when work is pressed against the tool, means are provided for preventing a twisting of either the inner or the outer end of the casing 46 with respect to the spindle. To this end a dowel pin 62 is arranged to project from the shoulder 44 of the spindle and the flange 48 upon the cas-

ing is provided with a suitable opening 64 for engagement with this pin 62 so that relative rotation between the spindle and the inner end of the casing is positively prevented. To prevent the outer end of the casing 46 from twisting with respect to the outer end of the spindle 16, the two are interlocked by means of a rigid member 68 of non-circular cross section secured to the rubber casing 46 and arranged to slip on to a co-operating non-circular end portion 66 of the spindle as the pad is applied thereto. This end portion 66 is shown as square to receive the rigid member 68 which, as illustrated, is in the form of a piece of square brass tubing perforated at 72 to allow the rubber of the outer end 70 of the casing, while the casing is being molded to shape, to unite firmly with the tubing 68 by flowing into the perforations.

The air pressure which is applied to inflate the casing of the tool tends not only to increase its diameter but as well to stretch it axially of the spindle. This tendency is prevented in the illustrated tool by anti-stretch means comprising a wire loop 74 passing through openings 76 in the square tubing 68 and extending along the molded rubber of the casing to its inner end where the ends 78 of the wire loop are turned outwardly within the flange 48 of the casing so that they are engaged by the clamping mechanism for the inner end of the casing, thereby positively preventing any elongation of the casing as a result of the air pressure applied.

The construction described imparts the necessary mechanical strength to a tool the dimensions of the outer end of which are less than can safely be utilized for the inner end which is to be clamped to the spindle. The tool is, therefore, especially suited for its intended use on the sharply curved breasts of some types of Louis heels.

A conical abrasive sleeve 80 is supported upon the conical resilient casing 46, this conical sleeve being held frictionally against a considerable strain. Additional means has also been provided for holding the abrasive sleeve 80 firmly in position upon the tool. To this end the inner end of the abrasive sleeve is slotted to form tabs which are turned outwardly at right angles to the axis of the sleeve to form a flange 82. The dimensions of the sleeve are such that when the tool is deflated, the sleeve may readily be slipped over the conical casing 46 to bring the flange 82 of the sleeve into engagement with the flange 48 of the casing, the washer 52 being then placed in position over both the sleeve and the casing, and the collar 50 being threaded on the spindle so as tightly to clamp both the sleeve and the casing. The collar 50 may, if desired, be provided with wrench sockets 84 to enable a spanner wrench to engage it and turn it tightly into clamped position.

In the operation of the machine, the spin-

dle 16 is driven to rotate the scouring tool 18, and air pressure is applied to the interior of the tool to inflate the pad 46. The operator then holds the shoe in inverted position with the heel part of the shoe away from him and placing the heel beyond the scouring tool 18, presents the breast of the heel to the rear side of that tool. It will be understood that the shoe is moved up and down to present the various portions of the breast of the heel to the tool and that by reason of the small dimensions of the tool, the operator is able to scour all parts of the breast of the heel without danger of damaging other portions of the shoe.

Having described the invention, what I claim as new and desire to secure by Letters Patent of the United States is:

1. In an abrading machine, a hollow rotary spindle supported at one end with its other end free, a resilient inflatable casing covering the free end of said spindle and having a closed end, an abrasive cover over said resilient casing, and means holding both said casing and said cover on the spindle constructed and arranged to effect an air-tight joint between the casing and the spindle.

2. In an abrading machine, a rotary buffering tool comprising an elongated tubular tapered pad of yieldable material having its large end open, a tapered abrasive cover therefor, and a rotary driving spindle for said pad secured to both ends of said pad, said spindle extending into the large open end of said pad and terminating within said pad at a point adjacent to the small end thereof.

3. In an abrading machine, a rotary buffering tool comprising an elongated tubular pad having its outer end smaller than its inner end, said pad being tapered internally and externally in the same direction, and a rotary driving spindle extending into said pad and tapered in the same direction as said pad, said spindle being secured to both ends of said pad.

4. In an abrading machine, a rotary spindle supported at one end and having a non-circular cross-section at its free end, a resilient casing on said spindle provided with a rigid member adjacent to one end adapted to fit over the non-circular end of the spindle, means for clamping said casing to the spindle, and an abrasive sleeve on said casing.

5. In an abrading machine, a rotary spindle, a resilient casing on said spindle, and means for preventing twisting of one end of said casing with respect to the spindle comprising a rigid member secured to said end of said casing and adapted to co-operate with a portion of the end of the spindle, said rigid member and said portion of the spindle having co-operating complementary portions of polygonal cross-section.

6. In an abrading machine, a rotary spindle, a resilient casing on said spindle,

means for preventing twisting of one end of said casing with respect to the spindle comprising a rigid member secured to the end of said casing and adapted to co-operate with a portion of the end of the spindle, said rigid member and said portion of the spindle having co-operating complementary portions of polygonal cross-section, and means for clamping the other end of the casing to the spindle.

7. In an abrading machine, a rotary spindle having a squared tip, a resilient casing adapted to be placed on said spindle and having a hollow member secured to the outer end of the casing and adapted to be engaged with and fit the squared tip of said spindle, and means for clamping said casing to said spindle.

8. A scouring tool adapted to be mounted upon a rotary driving means and comprising an elastic supporting casing arranged to support an abrasive cover, and a tubular insert within and attached to said supporting casing, said insert being constructed and arranged to co-operate with a driving means thereby to prevent twisting of the outer end of the supporting casing with respect to said means.

9. A scouring tool comprising a resilient supporting casing one end of which is adapted to be secured to a rotary spindle, and anti-twisting means sleeved on said spindle and secured to the other end of the supporting casing constructed and arranged to hold the outer end of said casing against rotation with respect to the spindle.

10. A rotary buffering tool, comprising an elongated pad of yieldable molded material, and a rigid hollow member of internal and external non-circular cross-section, the material of said pad at one end thereof being molded about said rigid member non-rotatably to secure said end of said pad to said member and the interior of said member being adapted to engage a complementary non-circular shank on a rotary drive member non-rotatably to couple said rigid member to said drive member to rotate said end of said pad.

11. A rotary buffering tool, comprising an elongated tapered pad of yieldable material, and a rigid member having a portion of non-circular cross section, the material of the pad at the small end thereof being molded about said rigid member to secure said end of said pad to said member, and said member being constructed and arranged to provide for non-rotary attachment to a rotary driving means.

12. A rotary buffering tool, comprising an elongated pad of yieldable material, and a rigid tubular member having perforated portions, the material of said pad at one end thereof being molded about said rigid member and into the perforations thereof to insure a positive interlocking bond between said pad and said member, and means for

attaching said member to a rotary driving means.

13. In an abrading machine, a rotary spindle, a tubular pad of yieldable material having an open end to receive said spindle, means for clamping said open end of said pad to said spindle, and a pin extending into the material of said pad adjacent to said open end thereof and engaging said spindle for positively preventing rotation of said open end of said pad relative to said spindle.

14. In an abrading machine, a rotatable spindle having a shoulder, a scouring tool comprising a resilient casing adapted to support an abrasive cover and provided at one end with an enlarged portion, means for clamping said enlarged portion of the casing against said shoulder, and means for positively preventing twisting of the enlarged portion with respect to the spindle.

15. In an abrading machine, a rotatable spindle having a shoulder, a scouring tool comprising a resilient casing provided at one end with an enlarged portion and adapted to support an abrasive cover, means for clamping said enlarged portion of the casing against said shoulder, and means for preventing twisting of both ends of the resilient supporting casing with respect to the spindle.

16. In an abrading machine, a hollow spindle rotatably supported at one end and having a shoulder near said end, the tip of said spindle being squared, an elastic casing on said spindle having a flanged portion for engagement with said shoulder and having secured thereto a piece of square rigid tubing for engagement with said tip, means for clamping the flanged portion of said casing to said shoulder on the spindle, and an abrasive cover over said casing.

17. In an abrading machine, a hollow spindle rotatably supported at one end and having a shoulder near said end, the tip of said spindle being squared, an inflatable elastic casing for said spindle having a flanged portion for engagement with said shoulder and provided with a piece of square tubing constructed and arranged to engage said tip to prevent relative twisting of the outer end of the casing and the tip, means for clamping said casing to said spindle constructed and arranged positively to prevent relative twisting of the inner end of the casing and the spindle, an abrasive cover for said casing, and means extending from said tubing to said clamping means arranged to prevent axial stretching of the casing.

18. In an abrading machine, a rotatable spindle, a scouring tool comprising a resilient supporting casing arranged to receive an abrasive cover, means for clamping one end of said casing to the spindle, anti-twisting means for preventing twisting of the other end of the casing, and means coacting with

said clamping means for securing said anti-twisting means against movement axially of the spindle.

19. In an abrading machine, a hollow spindle rotatably supported at one end and having its free end provided with a shoulder, the tip of said spindle being squared and said spindle being provided with air-outlet openings between the tip and the shoulder, an inflatable elastic casing for the free end of said spindle having a flanged end adapted to abut against the shoulder on the spindle, a square tubing secured to the free end of said casing and adapted to be sleeved on the tip of the spindle to prevent twisting of the outer end of the casing, a wire secured to said tubing and extending to the flange of the casing, a collar for clamping said flange and the wire against the shoulder of the spindle, and an abrasive cover for said casing.

20. A rotary buffing tool, comprising an elongated pad of yieldable material and having an inner and an outer end, said inner end being adapted to be secured against both rotary and axial movement to a rotary driving means, a rigid member secured against rotary and axial movement to the outer end of said pad and being adapted to non-rotary attachment to said driving means, and a wire loop adapted to be held by said driving means for securing said member against axial movement to said driving means.

21. In an abrading machine, a rotary spindle, an inflatable resilient casing on said spindle, means for clamping the inner end of the casing to the spindle, a rigid member secured against rotary and axial movement to the outer end of said pad and being adapted for non-rotary attachment to said driving means, and means within said casing arranged to prevent longitudinal movement of the rigid member at the end of the casing with respect to the spindle.

22. In an abrading machine, a rotatable spindle, a scouring tool adapted to be supported upon said spindle, said tool comprising a resilient supporting casing for an abrasive cover, means for clamping one end of said supporting casing to the spindle, and means extending from and held by said clamping means constructed and arranged to hold said supporting casing against stretching axially of the spindle.

23. A scouring tool adapted to be supported upon a rotary driving means, said tool comprising a supporting casing of resilient material adapted to be detachably secured to said driving means at one end, and metallic means carried by said casing and extending lengthwise of the supporting casing arranged to prevent axial stretching of the casing.

24. In a buffing machine, a rotary spindle, a resilient casing having an open end, said spindle extending into said casing through said open end thereof, means for securing

5 said casing at the open end thereof to said spindle to prevent relative longitudinal and rotary displacement between said end of said casing and said spindle, a member secured to
10 the opposite end of said casing, said member and said spindle having cooperating complementary portions of non-circular cross-section for preventing relative rotary displacement between said opposite end of said casing and said spindle, and means for preventing longitudinal displacement between said opposite end of said casing and said spindle.

15 25. In an abrading machine, a spindle rotatably supported at one end and having its other end free, a yieldable casing mounted on said spindle and adapted to receive and support an abrasive cover, means for clamping one end of said casing to said spindle
20 at a locality remote from the free end of the spindle, the other end of said casing extending beyond the free end of the spindle, and a member secured to said spindle and having a tubular portion within said yieldable casing
25 attached to said other end of said casing and slidably mounted over the free end of said spindle for supporting said casing.

In testimony whereof I have signed my name to this specification.

30 CAROLINE E. COSGROVE.
Administratrix of the Estate of John W. Cosgrove, Deceased.
